(57) CLAIM

The ornamental design for a shoe sole, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front medial side perspective view of a shoe sole showing the new design, according to a first embodiment; FIG. 2 is another front medial side perspective view thereof; FIG. 3 is a rear medial side perspective view thereof; FIG. 4 is a bottom view thereof;

FIG. 5 is a lateral side view thereof;

FIG. 6 is a medial side view thereof;

FIG. 7 is a front medial side perspective view of a shoe sole showing the new design, according to a second embodiment;

FIG. 8 is another front medial side perspective view thereof;

FIG. 9 is a rear medial side perspective view thereof;

FIG. 10 is a bottom view thereof;

FIG. 11 is a lateral side view thereof; and,

FIG. 12 is a medial side view thereof.

The broken lines and the grayed out portions surrounded by broken lines depict portions of the shoe sole that form no part of the claim.

A left-foot shoe is illustrated in FIGS. 1–12. Further embodiments of the claimed design include a right-foot shoe, which are mirror images of the views of the first and second embodiments in FIGS. 1–12.
